G. B. Massey,

Steam Indicator.

NO. 106,598.

Patented Aug. 23, 1870.

United States Patent Office.

GIDEON B. MASSEY, OF NEW YORK, N. Y., ASSIGNOR TO MASSEY LOW-WATER DETECTOR COMPANY, OF NEW YORK CITY.

Letters Patent No. 106,598, dated August 23, 1870.

IMPROVEMENT IN LOW-WATER AND HIGH-PRESSURE ALARM.

The Schedule referred to in these Letters Patent and making part of the same

To all whom it may concern:

Be it known that I, GIDEON B. MASSEY, of the city, county, and State of New York, have invented a new and useful Improvement in Low-water and High-pressure Alarm; and I do hereby declare that the following is a full, clear, and exact description thereof, which will enable others skilled in the art to make and use the same, reference being had to the accompanying drawing forming part of this specification.

My invention relates to low-water and high-pressure indicators, and my object is to provide more sure and effective means for lifting the steam-valve.

I will now describe my improvements in connection with such other parts as are necessary to a clear understanding thereof, and then point out and specify the said improvements in the claim.

In the accompanying drawing—

Figure 1 represents a front view of the instrument, partly in section, seen as when attached to the head of a steam-boiler.

Figure 2 is a sectional side view of the same.

Similar letters of reference indicate corresponding parts.

A represents the boiler.

B B is a double tube, connected with the boiler below the water-line, as seen at C. The double tube forms a rectangle.

The two uprights are connected, at the top and bottom, by short horizontal tubes, as seen in the drawing, D being the lower horizontal tube.

This short tube D is connected with the boiler by means of the tube E, as seen in fig. 2.

F is a partition in the tube E, which divides it, and also the tube D, into two parts. One part communicates with one of the long vertical tubes B, and the other part with the other long tube.

By means of this partition, an unobstructed channel is formed through the double tube, so that, when the water in the boiler falls to the dangerous point, as at c, steam will enter, and effectually exclude any water which may be retained in the double tube by reason of a vacuum in its upper part, and expand the tube by imparting heat thereto.

By this position, I secure two independent connections with a steam-boiler, so that, when the water descends below a given point, the steam will enter one, and force the water out through the other. In a sin-

gle connection, on the other hand, the steam must rise through the water, which will condense it, and create delay.

The rod G of the steam-whistle valve is connected with the upper short horizontal tube H by means of the swivel-nut I, in which nut the end of the rod works, and is made adjustable.

J is a central tube, which connects the parts of the whistle together, containing a spiral spring, K, around the valve-stem G, which spring acts against a collar on the stem at its lower end, and against the end of the spring-adjusting screw, L, at its upper end.

It will be seen that the spring bears directly down upon the valve with a constant pressure, and with a force proportioned to the pressure of steam required, the tension of the spring being regulated by the screw L.

M is a gauge-cock.

N is a tube, which connects the whistle with the steam-space of the boiler.

When the pressure exceeds the power or tension of the spring, (as the latter may be adjusted,) the valve will be raised, and the whistle will give the alarm.

It will be seen that the whistle-valve may be so adjusted upon its seat, by means of the swivel-nut, that the least expansion or increase in length of the double tube B B will raise it from its seat, and give the alarm for low water.

The adjustment of the valve for high steam and for low water, it will be seen, are entirely distinct and independent of each other, the result of high steam or over pressure, as well as of low water, being to raise the valve, and sound the alarm.

A sliding tube or other device may be arranged over the adjusting apparatus of the whistle-valve, so that the adjusting-screws may be inclosed and locked, to prevent tampering with the valve.

Having thus described my invention,

I claim as new and desire to secure by Letters Patent—

The combination, with a boiler and continuous tubing B H B, of the partitioned connecting-tubes E F D, as and for the purpose described.

GIDEON B. MASSEY.
